August 15, 1941, Serial No. 407,053.
In Great Britain August 16, 1935

10 Claims. (Cl. 260—240)

This invention relates to the production of dye-stuffs.

It is an object of this invention to produce compounds comprising two heterocyclic nitrogen nuclei linked by a chain of atoms including one or more nitrogen atoms.

According to the process of the present invention, dyestuffs are obtained by condensing a quaternary salt of a heterocyclic nitrogen compound having a reactive thio-ether or seleno-ether group or a reactive amino-vinyl, acyl-amino-vinyl, aryl-amino-vinyl, or acyl-aryl-amino-vinyl grouping in the α or γ position to a nitrogen atom with an organic compound containing two amino groups linked by a single bond or by a conjugate chain of carbon atoms some or all of which form part of one or more aromatic carbo-cyclic rings, and which may be represented by the general formula

where n is 0 or a positive integer, or salts of such compounds.

Examples of such compounds are: hydrazine, $\text{H}_2\text{N}-\text{NH}_2$ the o- and p-arylene diamines such as o- and p-phenylene-diamines

benzidine and its homologues such as dianisidine

diamino-stilbenes such as 2:2', 2:4', and 4:4'-diamino-stilbenes, e. g.

The reaction may be carried out in the presence of a solvent with or without an acid binding agent. When an acid binding agent is required, e. g. when using salts of these compounds, the reaction may be carried out in a neutral solvent such as alcohol together with an acid binding agent such as sodium ethoxide or sodium acetate, or it may be carried out in the presence of a basic solvent such as pyridine which acts as the acid binding agent.

The heterocyclic nitrogen compound whose

quaternary salt is to be employed may consist of any one of the well known heterocyclic nitrogen compounds such as substituted and unsubstituted thiazoles, thiazolines, oxazoles, oxazolines, selenazoles, selenazolines, pyridines, quinolines, indolenines, diazines, e. g., pyrimidines, thiadiazoles and quinazolines, and the corresponding polycyclic compounds such as benzthiazoles, naphththiazole and anthrathiazole.

It is believed that the reaction may take place in accordance with the following equations:

(3)

Many of the products of the present invention are coloured and are sensitizers for photographic silver halide emulsions. The dyestuffs obtained by the reaction of quaternary salts of heterocyclic nitrogen compounds having reactive aminovinyl or substituted aminovinyl groups with organic compounds such as hydrazine which may be represented by the formula

where n is 0 or a positive integer are particularly good sensitizers, and the present invention includes a photographic silver halide emulsion sensitised with such a dyestuff.

One or more of the dyestuffs may be incorporated in the photographic silver halide emulsion before it is coated on a support, or alternatively the support (e. g. a film or plate) coated with the emulsion may be bathed in a solution of one or more of the dyestuffs. The actual quantity incorporated may vary to a certain extent with the individual dyestuff and with the ultimate effect which it is desired to obtain; as an indication, however, of the order of the quantities which may be employed, 100 ccs. of a one in one thousand solution of the dyestuff may be incorporated in six and a half litres of emulsion equivalent to about 250 grams of silver nitrate, or the coated support may be bathed in a one in one thousand solution of the dyestuff; the strength of the solution may vary according to the dyestuff used and may be as low as one in ten thousand.

The process of the present invention is illustrated by the following specific examples.

Example 1

5.43 gms. of 1-methylmercapto-benzthiazole and 5.58 gms. of methyl-p-toluene sulphonate were fused together for four hours at 130-140° C. 1.56 gms. of hydrazine-hydrochloride and 50 ccs. of pyridine were then added and the mixture boiled for half an hour. Crystals formed in the solution even when hot. The solution was poured into cold water, when a heavy precipitate of almost colourless crystals was formed. These were collected and washed and re-crystallised. The purified crystals melted at 257° C. The corresponding ethyl compound, was formed in similar manner, using ethyl-p-toluene sulphonate in place of methyl-p-toluene sulphonate and was obtained as colourless crystals melting at 192° C.

Example 2

6.03 gms. of 1 ethylmercapto-quinoline, and 5.58 gms. of methyl-p-toluene sulphonate were heated together for four hours at 130-140° C. when the solid quaternary salt was formed. 1.6 gms. of hydrazine-hydrochloride and 30 ccs. of pyridine were then added and the whole maintained at a temperature just below the boiling point for about half-an-hour. The mixture was then poured into water and the red crystals which formed were filtered off, washed with water and spirit and ether and dried and re-crystallised from methyl alcohol as scarlet plates, melting at 258° C. The corresponding ethyl compound, was prepared in a similar manner but using ethyl-p-toluene sulphonate in place of methyl-p-toluene sulphonate and formed scarlet needles and rods melting at 194° C.

Example 3

4.95 gms. of 1-methylmercapto-benzoxazole and 5.58 gms. of methyl-p-toluene sulphonate

were heated together at 130-140° C. for four hours. 1.6 gms. of hydrazine-hydrochloride and 30 ccs. of pyridine were then added and the whole mixture boiled for half-an-hour. The mixture was then poured into cold water and a precipitate of fine white crystals was formed. These were collected, washed and dried and the melting point was found to be 277° C.

Example 4

1.78 gms. of dimethylthiolthio-($\beta\beta'$)-diazole and 1.88 gms. of methyl-p-toluene sulphonate were heated together for 3½ hours at 120-130° C. After cooling 0.6 gm. of hydrazine hydrochloride and 12 ccs. of pyridine were added and the mixture was gently warmed until solution was effected, after which it was gently boiled under a reflux condenser for half-an-hour. The mixture was then poured into 200 ccs. of water, when light coloured crystals separated out. These were collected and washed and re-crystallised from methyl alcohol to yield light yellow plates melting at 170-172° C.

Example 5

1.78 gms. of dimethylthiolthio-($\alpha\beta'$)-diazole and 1.88 gms. of methyl-p-toluene sulphonate were heated together for 3½ hours at 120-130° C. The mixture was allowed to cool and 0.6 gm. of hydrazine hydrochloride and 12 ccs. of pyridine were then added and the whole was gently warmed until solution was effected, after which the mixture was gently boiled under a reflux condenser for half-an-hour. The mixture was then poured into 200 ccs. of water, when whitish crystals separated out. These were collected and washed and re-crystallised from benzene to yield almost colourless plates melting at 282-3° C.

Example 6

1.76 gms. of 4-methylthiolquinazoline and 1.86 gms. of methyl-p-toluene sulphonate were heated together at 130-140° C. for four hours. 0.6 gm. of hydrazine dihydrochloride and 25 ccs. of pyridine were then added and the mixture was gently warmed until the solid was dissolved. The mixture was then gently boiled under a reflux condenser for half an hour after which it was poured into water and allowed to stand. The yellow solid which separated out was collected, washed and re-crystallised to give bright yellow crystals melting at over 310° C.

Example 7

0.87 gm. of 1-methylquinoline-4-thione and 0.98 gm. of methyl-p-toluene sulphonate were heated together at 130° C. for about 3½ hours. 0.265 gm. of hydrazine dihydrochloride and 15 ccs. of pyridine were then added and the mixture was gently boiled under a reflux condenser for about 30 minutes. The solution became deep orange in colour and solid separated out and the mixture was poured into water. The solid dissolved up in the water, but on allowing the mixture to stand small copper red crystals, melting at 160° C. separated out.

Example 8

3.62 gms. of 1-methylthiolbenzthiazole and 3.72 gms. of methyl-p-toluene sulphonate were heated together at 130-140° C. for about 3½ hours. 1.08 gms. of o-phenylenediamine and 40 ccs. of pyridine were then added and the mixture was gently heated until the solid was dissolved and then gently boiled under a reflux condenser for about 30 minutes. It was then poured into wa-

ter and allowed to stand when an oil separated out. This was separated off and extracted with boiling benzene. The benzene extract was cooled and a grey solid was precipitated from it, which was recrystallised from boiling benzene to yield an almost colourless solid, melting at 278° C.

Example 9

3.62 gms. of 1-methylthiol-benzthiazole and 3.72 gms. of methyl-p-toluene sulphonate were heated together at 130-140° C. for about 8½ hours. 1.45 gms. of p-phenylenediamine dihydrochloride and 40 ccs. of pyridine were then added and the mixture was gently warmed until all the solid was dissolved and was then gently boiled under a reflux condenser for about ½ hour. A pale yellow solid began to form and the mixture was poured into water when a light yellow precipitate was formed. This was filtered off, collected and washed and extracted with hot benzene. The extract was cooled and the solid which formed was recrystallised to give almost colourless crystals melting at 275° C.

Example 10

2.23 grams of 1:3:3-trimethyl-2- ω -acetanilido-vinyl-indolenium iodide and 1.05 gms. of hydrazine hydrochloride were mixed with 20 ccs. of pyridine and the whole warmed on a water bath for about half an hour when an orange dye formed. The mixture was then gently boiled under a reflux condenser for about twenty minutes. The liquid obtained was then poured into aqueous potassium iodide solution when the dye-stuff was precipitated out as a crimson solid and recrystallised from methyl alcohol to give a dye which decomposed at about 250° C. This dye is a very powerful sensitiser for silver chloride emulsions and extends their sensitivity ranges to about 5900 Å. with a flat sensitising curve over the range from about 4600 Å to about 5400 Å.

Example 11

22.3 grams of 1:3:3-trimethyl-2- ω -acetanilido-vinyl indolenium iodide and 9.05 grams of p-phenylenediamine hydrochloride and 200 ccs. of pyridine were mixed and heated together on a water bath for twenty-five minutes and then gently boiled under a reflux condenser for a further ten minutes. The orange solution obtained was then poured into water when small brick-red crystals quickly settled out. These were filtered off, washed with spirit and ether and dried and melted at 272° C.

Example 12

11.2 grams of 1- ω -acetanilido-vinyl-benzthiazole ethiodide, 4.5 grams of p-phenylenediamine hydrochloride were mixed together with 300 ccs. of pyridine. The solids dissolved up and the solution became yellow in colour. The solution was then heated on a water bath for forty minutes, after which it was gently boiled under a reflux condenser for ten minutes, when a crimson solid separated out. The mixture was then poured into water and the crimson crystals which separated out were filtered off, washed and dried. They melted at 285° C.

Example 13

21 grams of 1- ω -acetanilido-vinyl-benzoxazole methiodide and 9.05 grams of paraphenylenediamine hydrochloride were mixed with 100 ccs. of pyridine and gently boiled together. A deep yellow solution was obtained and orange coloured crystals were deposited from the hot solution.

After allowing this solution to stand until cool the crystals were filtered off, washed and dried. They had a melting point higher than 305° C.

Example 14

11.2 grams of 1- ω -acetanilido-vinyl-benzthiazole ethiodide and 2.7 grams of hydrazine dihydrochloride were mixed together with 100 ccs. of spirit and 4.1 grams of anhydrous sodium acetate. On gently warming the mixture a deep orange solution with a faint red tinge was obtained. This was diluted with water and brown crystals with a green reflex were deposited. These crystals were filtered off, washed and recrystallised from methyl alcohol and were found to melt at 226° C. with decomposition.

Example 15

22.3 grams of 1:3:3-trimethyl-2- ω -acetanilido-vinyl-indolenium iodide, 9.2 grams of benzidine and 150 ccs. of dry spirit were gently boiled together under a reflux condenser for 30 minutes. The substances dissolved in the spirit and then orange crystals with a bluish reflex separated from the hot solution. After cooling the solid was filtered off from the liquors and well washed with spirit and ether. The crystals melted above 300° C. A further experiment showed that this reaction could be carried out equally well using 30 pyridine in place of the alcohol.

Example 16

22.5 grams of 1- ω -acetanilido-vinyl-benzthiazole ethiodide and 9.2 grams of benzidine were mixed together with 200 ccs. of dry spirit and the whole gently boiled for 30 minutes. A brown crystalline solid separated out, which was filtered off, washed and dried and obtained as dark brown crystals melting at 260° C.

Example 17

21 grams of 1- ω -acetanilido-vinyl-benzoxazole methiodide and 9.2 grams of benzidine were mixed together with 100 ccs. of alcohol and the whole gently heated for a few minutes. An intense yellow solution was obtained from which small orange crystals separated out. These were filtered off and washed and dried and obtained as orange yellow powder having a melting point above 300° C.

Example 18

18.1 grams of 1-methylthiol benzthiazole were heated together with 18.6 grams of methyl-p-toluene sulphonate for three and a half hours at 130-140° C. 18.4 grams of benzidine and 200 ccs. of spirit were added and the mixture was gently warmed for twenty minutes when a light yellow solid was deposited and mercaptan evolved. The solid was filtered off, well washed with benzene, spirit and ether and obtained as almost colourless powder melting above 300° C.

Example 19

22.3 grams of 1:3:3-trimethyl-2- ω -acetanilido-vinyl indolenium iodide, 12.2 grams of di-anidine (2:2'-dimethoxy benzidine) and 100 ccs. of pyridine were mixed together and gently boiled under a reflux condenser for thirty minutes. A deep orange solution was obtained from which a brick red solid was deposited on cooling. This solid was filtered off, well washed and obtained as small brick red crystals, melting at 282° C. with decomposition.

This application is a division of copending ap-

lication Ser. No. 95,033, filed August 8, 1936, now Patent No. 2,307,049, issued January 5, 1943.

What I claim is:

1. A process for the production of dyestuffs which comprises condensing by heating together a quaternary salt of a heterocyclic nitrogen compound of the type used in cyanine dyes which contains a grouping selected from the group consisting of the amino vinyl, acylamino vinyl, arylamino vinyl and acylarylamino vinyl groupings in a position selected from the group consisting of the α and γ positions to the heterocyclic quaternary nitrogen atom with a second nitrogenous compound selected from the group consisting of diamine, diamines with two amino groups in which the two amino groups are separated by a chain of an even number not exceeding 10, of carbon atoms alternately doubly and singly bonded, the carbon atoms directly linked to the amino groups each forming with the next adjacent carbon atom in the chain part of a carbocyclic nucleus.

2. A process for the production of dyestuffs which comprises condensing by heating together a quaternary salt of a heterocyclic nitrogen compound of the type used in cyanine dyes which contains a grouping selected from the group consisting of the aminovinyl, acylamino vinyl, arylamino vinyl and acylarylamino vinyl groupings in a position selected from the group consisting of the α and γ positions to the heterocyclic quaternary nitrogen atom, with hydrazine in the presence of a solvent and acid binding substance.

3. A process for the production of dyestuffs which comprises condensing by heating together a quaternary salt of a heterocyclic nitrogen compound of the type used in cyanine dyes which contains a grouping selected from the group consisting of the aminovinyl, acylamino-vinyl, arylamino vinyl and acylarylamino vinyl groupings in a position selected from the group consisting of the α and γ positions to the heterocyclic quaternary nitrogen atom, with an arylene diamine in the presence of a solvent and acid binding substance.

4. A process for the production of dyestuffs which comprises condensing by heating together a quaternary salt of a heterocyclic nitrogen compound of the type used in cyanine dyes which contains a grouping selected from the group consisting of the aminovinyl, acylamino vinyl, arylamino vinyl and acylarylamino vinyl grouping in a position selected from the group consisting of the α and γ positions to the heterocyclic quaternary nitrogen atom, with a polynuclear arylene diamine in the presence of a solvent and acid binding substance.

5. A process for the production of a dyestuff comprising reacting 1:3:3-trimethyl - 2 - ω -acet-anilidovinyl indolenium iodide with hydrazine by heating them together in the presence of a solvent and an acid binding substance.

6. A process for the production of a dyestuff comprising reacting 1- ω -acetanilidovinyl-benz-thiazole ethioidide with hydrazine by heating them together in the presence of a solvent and an acid binding substance.

7. A process for the production of a dyestuff comprising reacting 1:3:3-trimethyl - 2 - ω -acet-anilidovinyl indolenium iodide with benzidine by heating them together in the presence of a solvent and an acid binding substance.

8. A compound selected from the group consisting of dyestuffs of the general formula:

wherein D and D_1 are the residues of heterocyclic nitrogen compounds of the type used in cyanine dyes, R and R_1 are alkyl groups and p is a positive integer not greater than 2 and the acid salts of such dyestuffs.

9. A dyestuff of the formula:

which is a crimson solid melting and decomposing at about 250° C. giving an orange solution in alcohol and extending the sensitivity of silver chloride emulsions to about 5900 Å. with a flat sensitizing curve over the range from about 4600 Å. to about 5400 Å.

10. A dyestuff of the formula:

50 which is in the form of brown crystals with a green reflex giving an orange-red solution in alcohol, melting at 226° C. with decomposition and extending the sensitivity range of photographic silver halide emulsions.

JOHN DAVID KENDALL.
